[54] TEA BAG SQUEEZER

[76] Inventor: Louis A. Carson, 1432 Erin Ave.,
Upland, Calif. 91786

[] Term: 14 Years

[21] Appl. No.: 876,548

[22] Filed: Feb. 9, 1978

[51] Int. Cl. .... D7—04
 [52] U.S. Cl. D7/47; D7/105
 [58] Field of Search D7/161, 48, 47, 99,
D7/140, 105, 161, 209; 294/8.5, 16, 33, 99 R, 7,
8; 30/324; 100/234

[56] References Cited

U.S. PATENT DOCUMENTS

D. 138,917	9/1944	Frank	D7/105
D. 173,254	10/1954	Bassler	D7/105
967,263	8/1910	Sweeting	294/7
1,627,880	5/1927	Baxter	294/33
2,483,985	10/1949	Sonn	D7/105 X
4,037,793	7/1977	Puustinen	D7/47 X

Primary Examiner—Winifred E. Herrmann

Attorney, Agent, or Firm—Poms, Smith, Lande & Rose

[57] CLAIM

The ornamental design for a tea bag squeezer, as shown and described.

DESCRIPTION

The FIGURE is a perspective view of a tea bag squeezer showing my new design; the side opposite that shown is identical thereto.

U.S. Patent

Mar. 18, 1980

Des. 254,466